No. 625,630.

J. A. YARTON.

Patented May 23, 1899.

OIL GAS LAMP.

(Application filed Jan. 14, 1899.)

(No Model.)

FIG.1.

UNITED STATES PATENT OFFICE.

JAMES A. YARTON, OF OMAHA, NEBRASKA, ASSIGNOR TO THE AUTOMATIC GAS LAMP COMPANY, OF SAME PLACE.

OIL-GAS LAMP.

SPECIFICATION forming part of Letters Patent No. 625,630, dated May 23, 1899.

Application filed January 14, 1899. Serial No. 702,179. (No model.)

To all whom it may concern:

Be it known that I, JAMES A. YARTON, of Omaha, in the county of Douglas and State of Nebraska, have invented a new and Improved Oil-Gas Lamp, of which the following is a full, clear, and exact description.

My invention relates to an improvement in oil-gas lamps, or lamps of that kind which use oil for fuel, but transform it into gas before burning.

My invention comprises an improved form of generator and shield therefor, together with a method of supporting the lamp so that it may be swung to one side, and thus drawn from under the generator.

My invention also comprises an improved construction of the controlling-valve, whereby any sediment which may be in the oil is prevented from entering the generator-tube.

My invention further comprises the novel features hereinafter described and claimed.

Reference is to be had to the accompanying drawings, forming a part of this specification, in which similar characters of reference indicate corresponding parts in all the figures.

Figure 1 is an elevation of my lamp with portions thereof shown in section. Fig. 2 is a sectional elevation, on a larger scale, of the controlling-valve and the swivel-support for the lamp. Fig. 3 is a section taken upon the line 3 3 of Fig. 1, with the lamp swung to one side, so as to clear the generator; and Fig. 4 is an end view of the shield covering the generator-tube.

The lamp is intended for use in connection with an incandescent mantle, the burner itself being, however, of the ordinary form. The oil is contained in an elevated reservoir C, which is supported from a feed-tube A by means of a brace a' and by the supply-tube C', which connects the lower end of the reservoir with the feeding-tube A, which connection is made by means of an ordinary T A'. A continuation A² of the feeding-pipe extends downward and is screwed or otherwise secured to the valve-casing B, which is shown in section and on an enlarged scale in Fig. 2, and is provided with an upwardly-extending sleeve B', threaded interiorly to receive the tube A², and is also provided with a horizon-

tally-extending sleeve B², which is interiorly threaded to receive the generator-tube H. The casing has a central passage or chamber E, which is in line with the feeding-tube A². This passage or chamber is extended upward 55 into the feeding-tube A² by means of a short section of smaller tube D, which provides a chamber between the small tube D and the feeding-tube A², designed to catch and hold any sediment which may be in the oil and 60 prevent its access to the generator. Surrounding the chamber E, within the valve-casing, and having a dividing-wall between the two is an annular chamber E', connected at its upper end by a passage E² with the 65 generator-tube H. Connection is made between the two chambers E and E' by means of a conical aperture extending through the separating-partition near the upper portion of each chamber. This aperture is placed as 70 far as convenient above the bottom of each chamber, so as to furnish further settling-chambers for the reception of any sediment which may be carried by the oil. The conical connecting-aperture is controlled by a 75 valve F, consisting of a threaded rod screwed into a sleeve B³ of the valve-casing and having a pointed end fitting the conical aperture. The stem of the valve is packed by means of a packing-sleeve F', which screws upon the 80 outer end of the sleeve B³.

The generator consists of a tube H, bent backward upon itself, as clearly shown in Fig. 1. The outer end of said tube is carried at a slightly-greater elevation than a portion 85 of the tube near the bend, said lowermost portion of the tube being located directly over the lamp-chimney when the lamp L is in the normal position, and thus a small reservoir is provided for any oil which may remain in the tube unvolatilized. Within the tube are one or more spiral coils of wire h, formed of copper or any other good heat-conducting material. As herein shown, this inner heat-conducting coil is formed of several 90 spiral coils of wire. The same end might be secured by the use of a single wire, placing the coils of the wire close together. The outer end of the tube H is closed by a hollow plug H', which screws into the end of the tube and 100

has a perforation h' for the escape of the gas. The spiral wires h extend close enough to the end of the tube so that the plug H' when screwed in place will press against the ends 5 of the wires. The end of the generator-tube is placed in front of the receiving end of the mixing-tube I , and the upper portion of this mixing-tube is formed as a part of a casting G , which may either form a part of the valve-casing B or, as shown in Fig. 1, be made separate therefrom and secured thereto. In Fig. 2 it is shown as secured to the valve-casing by means of a socket G' , which is interiorly threaded and screws upon a projecting plug 10 B^4 of the valve-casing. To the lower end of this casting is secured the mixing-tube proper, I , which extends downward and then curves horizontally and upward, carrying upon its lower end the burner and lamp L . The tube 15 I is supported by a swivel-joint, so that it may be turned upon its axis and the lamp swung from beneath the generator. The upper end of the tube I is provided with a collar I' of slightly larger diameter than the 20 tube and which is engaged by the lower end of a cap J , which screws upon the casting G , as shown at g . This connection serves to support the tube and hold its upper end against the casting G . For the purpose of 25 making a tighter joint the casting G is provided with a groove I^2 , which receives the end of the tube I . To more firmly support the tube I , the casting G is provided with a projecting sleeve or short tube G^3 , which enters 30 the upper end of the tube I and extends downward a sufficient distance to form a firm support therefor. It will be seen that by this construction the lamp may be swung to one side, so as to clear it of the generator and enable 35 the chimney to be readily removed. This position of the parts is shown in Fig. 3.

To better concentrate the heat upon the generator, it is covered by a shield, which is clearly shown in Figs. 1 and 4. This shield 40 is in cross-section of a V shape and has its outer end closed, the shield being placed immediately over the generator-tube. At the upper end of the shield it is provided with two arms k , which may be bent about the 45 valve-casing B , so as to hold the shield in position. This concentrates and holds the heat about the generator-tube H , so as to more efficiently volatilize the oil.

The feeding-tube A may be provided at its 50 upper end with a hook a , by means of which the lamp may be suspended.

It is evident that the burner may be swung from beneath the generator by permitting the casting G to turn upon the valve-casing B at 55 the point where it is screwed thereon, thus doing away with the necessity of the swivel connection between the tube I and the casting G . The result accomplished, which is the removal of the lamp from beneath the 60 generator, is the same as that accomplished by the swivel connection previously described.

In this case, however, the hood K should be either broadened at its open end or made short enough so as to not interfere with the swinging of the receiving end of the mixing-tube. This might also be accomplished by shortening the projecting sleeve G^2 , which acts as the receiving end for the mixing-tube. 70

Having thus described my invention, I claim as new and desire to secure by Letters 75 Patent—

1. In an oil-gas lamp, a mixing-tube carrying a burner at one end, a gas-generator discharging into the other end of the mixing-tube, said mixing-tube being formed in two sections, 80 one section having a flange near its end and the other having a groove to receive the end of the first section and a reduced portion entering the said first section, and a clamping-ring engaging said flange and screwing upon 85 the other section, substantially as described.

2. A supply-valve for oil-gas generators, comprising a casing to which the supply and generator pipes are attached, provided with a central passage extended up into the supply-pipe and forming therewith and within the same an annular settling-chamber, and with a passage leading from the central passage to the generator-pipe, and a valve for controlling communication between the said 95 passages, substantially as described.

3. A supply-valve for oil-gas generators, comprising a casing having attachments for the oil-supply and generator pipes at right angles to each other, said casing having a 100 central passage or chamber, and an annular chamber surrounding the first, and both in line with the oil-supply connection, the central chamber being connected with the oil-supply and the annular chamber connected 105 above its bottom with the generator, said casing having a connecting-passage between the central and the annular chambers, located above the bottom of each, whereby settling-chambers are formed, and a valve mounted 110 in the casing and adapted to close said connecting-passage, substantially as described.

4. A supply-valve for oil-gas generators, comprising a casing having attachments for the oil-supply and generator pipes, at right 115 angles to each other, said casing having a central passage or chamber, and an annular chamber surrounding the first, both being in line with the oil-supply connection, the central chamber being extended upward into the 120 oil-supply connection by a small tube, thus forming a settling-chamber about said tube, the annular chamber being connected above its bottom with the generator, the casing having the connecting-passage between the central and annular chambers located above the 125 bottom of each, whereby additional settling-chambers are formed, and a valve mounted in the casing and adapted to close said connecting-passage, substantially as described.

5. A generator, provided with a suitable heat-conducting filler, and a tip entering the 130

end of said generator and adjustable to be in direct contact with said heat-conducting filler, substantially as described.

6. The combination with a valve-casing, having the valve-seat at the bottom of the generator-socket, and a generator-tube inserted in said socket, of a wire filler within said tube extending to and contacting with the valve-seat, and a tip within the other end of the generator-tube and adjustable to contact with the wire filler, substantially as described.
- 5 7. The combination with a valve-casing, having the valve-seat at the bottom of the gen-

erator-socket, and a generator-tube inserted in said socket, of a wire filler within said tube extending to and contacting with the valve-seat, and a tip within the other end of 15 the generator-tube and adjustable to contact with the wire filler, substantially as described.
